UNITED STATES PATENT OFFICE.

WILBUR AUGUST HEIDEL, OF MANKATO, MINNESOTA.

MATRIX-MAKING MACHINE.

1,098,947.

Specification of Letters Patent.

Patented June 2, 1914.

Application filed November 23, 1912, Serial No. 733,185. Renewed April 16, 1914. Serial No. 832,383.

To all whom it may concern:

Be it known that I, WILBUR A. HEIDEL, a citizen of the United States, and a resident of Mankato, in the county of Blue Earth and State of Minnesota, have made certain new and useful Improvements in Matrix-Making Machines, of which the following is a specification.

My invention relates to composing machines of the kind often designated in this art as linotype machines.

My invention comprehends a number of improvements for accomplishing a considerable number of objects, among which are the following: I. To simplify the construction so as to enable the mechanism to be used where composing machines have heretofore been found impracticable on account of their cost. II. To provide for recording, from time to time, the matter to be printed and preserving a paper record of such matter, to be used as a matrix from which slugs or stereotype plates may be made whenever needed. III. To simplify the type bar mechanism so that a number of independent type bars may be lowered to different levels, each type bar carrying a plurality of type, the parts being so arranged that the letters to be printed in a line are brought together by virtue of the different levels of the several type bars. IV. To provide improved mechanism for restoring the several type bars to a predetermined level which they normally occupy. V. To provide for properly alining and clamping the type in suitable position to enable them to make an impression or some equivalent step contemplating the printing of a line. VI. To improve the locking and spacing mechanism for holding the various type characters in suitable position for making impressions.

Reference is made to the accompanying drawings forming a part of this specification and in which like letters indicate like parts.

Figure 1 is a front elevation of my improved composing machine complete and ready for use; Fig. 2 is a side elevation of the same; Fig. 3 is an enlarged fragmentary side elevation corresponding to the middle portion of Fig. 2 but showing certain movable parts as occupying positions different from those represented in said figure; Fig. 4 is a fragmentary side elevation corresponding to the middle portion of Fig. 2 but enlarged relatively thereto; Fig. 5 is a detail

being a section on the line 5—5 of Fig. 6 looking in the direction of the arrow and showing the means for supporting the type bars; Fig. 6 is a section on the line 6—6 of Fig. 5 looking in the direction of the arrow and showing a number of type bars together with means for temporarily supporting the same preparatory to making an impression from the types; Fig. 7 is a section on the line 6—6 of Fig. 5 but showing the type bars alone; Fig. 8 is a fragmentary perspective showing the upper portions of two top bars and their guide wires; and, Fig. 9 is a fragmentary section on the line 9—9 of Fig. 1 looking in the direction of the arrow.

A pair of base bars are shown at 10, and extending upwardly from them are two side bars 11—12. A top bar 13 extends across from one side bar to the other. Connected with the side bars 11—12 and extending forwardly therefrom and toward each other, are brace bars 14—14, 15—15, and supported upon these brace bars are a pair of front bars 16—17, which extend throughout practically the height of the machine. I provide a number of pedestals 18 all exactly alike, only one being shown in Fig. 1. Each pedestal carries a stationary sector 19 which is provided with notches 20, and also with the letters of the alphabet, as shown in Fig. 1, or with any other characters or intelligible marks or symbols to be printed. The number of sectors employed should equal the number of type bars and as a consequence should equal the maximum number of letters and spaces in a full line. I find it very convenient to use fifty-two letters upon each sector—that is to say, twenty-six capitals and twenty-six lower case letters, the number of notches 20 in any event corresponding to the number of letters or other characters with which the sector is provided.

Associated with each sector is a key lever 21 journaled upon a pivot rod 22 and adapted to be turned angularly by hand. The key lever carries a pawl 23 which lodges in any one of the notches 20, as the lever is turned upon its pivot rod, so as to hold the lever in such position that its outer end is associated with some one letter or character. The lower portion of the key lever 21 is provided with a slot 24, and extending through this slot is a pivot pin 25. A rod 26 carries this pivot pin and each of these

rods is connected by a pivot pin 27 with the lower end of a corresponding supporting bar 28. Each supporting bar is slightly inclined, as indicated in Fig. 2, and is provided upon one of its edges with a number of teeth 29 corresponding to the number of letters or other characters to be printed by the machine. The several supporting bars are journaled upon a rod 30, the latter extending through two brackets 31 which project backwardly from the top of the side bars 12.

10 A number of guiding wires 32 extend through the top bar 13 and also through a bottom bar 13^a, disposed parallel with the top bar, yet located at the bottom of the machine. Each guiding wire 32 is provided at its lower end with a head 32^a and is fitted at its upper end with a nut 32^b. By aid of this 15 nut the guiding wire may be given any desired degree of tension—the idea being to render it straight at all times.

The type bars are shown at 33. Each is an elongated flat bar of metal provided with 20 a number of type notches 34, and is adapted to bend slightly when pressed upon at a convenient point adjacent its middle portion, as hereinafter described. I also provide a guide bar 35 (see Fig. 1) having generally the form of a type bar but carrying 25 no types. The guide bar in question is placed at the left of the type bars according to Fig. 1, and is the end bar of the series. Its purpose is to provide a vertically disposed flat surface in order to keep the adjacent vertical row of types, carried by the 30 type bar next to the guide bar and parallel therewith, in proper position, so that the types cannot drop off the type bars or become displaced. Each type bar is adapted 35 to bind against the types carried by the next successive type bar, whenever the type bars are crowded together as hereinafter described. The various type bars 33 and the 40 guide bar 35 are severally provided with guide arms 36—37, these arms having eyes 36^a—38 which encircle the guide wires 32. Each guide arm 37 is provided with a finger 38^a integral with it and extending laterally 45 and backwardly from it, as indicated in Fig. 6. The purpose of the fingers 38^a is to 50 lodge upon the shoulders 29 and support the type bars or guide bar, as the case may be, the level at which the same is supported being determined by the level at which the 55 finger 38 engages the particular shoulder 29 upon which it rests, and this level in turn being controlled by the degree of inclination given to the supporting bar 28.

60 Located near the bottom of the frame of the machine and having a slight vertical play relatively thereto, is a lifting bar 38^b provided with teeth 38^c, each having generally the form of a fork, the several forks 65 straddling the guide wires 32, as indicated

in Fig. 6. The purpose of the lifting bar 38^b is to raise the several type bars and the guide bar 35 into a predetermined plane which they normally occupy. For the purpose of raising the lifting bar 38^b I provide 70 cords 39 which extend partially around pulleys 40—41. The pulleys 40 are mounted upon the side bars 11—12, and the pulleys 41 are carried upon the upper ends of the two arms 42. These arms are connected rigidly 75 with a shaft 43, which extends through the base of the framework of the machine. Connected with the arms 42 is a lever 44. By raising the outer or free end of this lever, the arms 42 are swung backward so as to 80 tighten the cords 39, and thus elevate the lifting bar 38^b. The types are shown at 45, and are located loosely upon the type bars. Each type is provided with two lugs 46, which fit neatly against the adjacent edges 85 of the type bar upon which the type is carried. Each type is further provided with a face 48, which in this instance is an impression face. By this arrangement each type is loose upon the type bar carrying it, 90 but has no appreciable degree of play.

Carried by the front bars 17 are two pairs of arms 51 and 52 (see Fig. 2), the arms 51 supporting a roll 53 of impression paper—that is, paper of considerable thickness, and 95 made soft enough to receive an impression from type for purposes of stereotyping. The arms 52 support a roll 54 and the web of paper, which is shown at 55, winds off from the roll 53 and onto the roll 54. A ratchet 100 wheel 56 is connected with the roll 54 for the purpose of turning the latter step by step. A pawl 57 engages the ratchet wheel 56 and turns the latter. This pawl is pivotally mounted upon a hand lever 58, this 105 lever being mounted upon a shaft 59 journaled upon short arms 60.

Rigidly mounted upon the shaft 59 at the end thereof opposite the hand lever 58 is an arm 61, which is at all times parallel with 110 the upper portion of the hand lever. A platen 62 having the form of a flat bar is connected rigidly with the arm 61, and with the lever 58, so that a swinging movement of the hand lever 58 causes the platen 62 to 115 move, in the arc of a circle, to the same extent as the hand lever. The hand lever and the arm 61 are provided with notches 63, and adjacent to these notches are guide pins 63^a, which extend across from the hand lever 120 58 to the arm 61. The guide pins 63^a are for the purpose of guiding the web 55 of paper as it is fed downwardly step by step, in accordance with the movements of the hand lever 58, and a consequent step by step 125 rotation of the ratchet wheel 54. Mounted upon the side bars 11—12 are guide plates 64—65 provided with inclined edges 66—67, between which is a substantially V-shaped opening, as indicated in Fig. 4. A pair of 130

wedge bars 68—69 are located within this opening. Each of these wedge bars has in cross section the form of a truncated wedge, and the wedge bars are supported upon the hand lever 58 and arm 61 by aid of stout spiral springs 70—71, so as to have a slight degree of movement relatively to other parts.

Pivots connected with the arm 61 and with the hand lever 58 are two links 72—73, which extend backwardly to the rear of the machine, and are there pivotally connected to the lower ends of two levers 74. Extending from one of these levers to the other is a bar 75, which is provided with a groove 76 of proper size and form to fit against the rear ends of the types 46. The levers 74 are pivotally mounted on brackets 77 disposed at opposite sides of the frame work. The parts are so arranged that when the hand lever 58 is pressed backward, that is to the right, according to Fig. 4, the bar 75, (see Fig. 9) is forced directly against the adjacent ends of the types for the purpose of alining them accurately. Mounted upon one of the guide plates 67 is a bracket 78, and pivoted upon the latter is an arm 79 provided with a portion 80, bent inwardly toward the center of the machine, and extending through a hole 80^a, so as to engage the guide bar 35.

Carried by the arm 61 is a bracket 81 which partially encircles the arm 79. Whenever the hand lever 58 is moved so that the arm 61 moves with it, the bracket 81 by sliding along the arm 79 causes the portion 80 of this arm to be forced inwardly against the guide bar 35, thus tightening the particular row or line of type under consideration, or in other words temporarily locking a line of type just set, as will be understood from Fig. 9. Each type bar 33 carries at its lower end a spacer 82, having generally the form of a leaf spring of a substantially semi-circular shape and carried by a pin 83. The spacer normally tends to force the adjacent type bars on each side of it a distance apart rather greater than the thickness of a type bar, but when pressure is applied to the line by the arm 79, the several spacers yield to substantially the same extent as indicated in Fig. 9, so that the length of the line of type set is constant. The uppermost shoulder 29 of each supporting bar 28 is the one associated with the spacer 82 carried by the corresponding type bar.

The operation of my device is as follows:—The various parts being formed and assembled, as above described, and the paper rolls 55—56 with their web 55 being disposed as indicated, the operator first sees that the various hand levers are pushed back so as to occupy their respective normal positions (see Fig. 2). The lever 58 being in its normal position, is swung outwardly,

and the hand lever 44 being down as here shown, the various type bars are now supported upon the uppermost shoulders 29 of the respective supporting bars 28 and are all in the same plane. Suppose now that the operator wishes to compose a line. He draws the various levers 21 angularly forward one at a time, and in so doing causes the bottoms of the various supporting bars 28, corresponding to the respective letters and spaces to be used in the line, to swing backwardly and thus take up new positions at varying degrees of inclination. As each supporting bar 28 moves backwardly into its new position, the corresponding type bar 33 heretofore supported by the bar in question is now left unsupported so that it drops down and lodges against some one of the shoulders 29—the particular shoulder being determined of course by the inclination of the respective supporting bar 28, and this in turn being determined by the angular position of the appropriate lever 21 associated with the particular type bar and the particular supporting bar 28 in question. The type bars thus drop downwardly into different planes, but as the various type notches 34 carried by one type bar are always in registry with notches carried by the other type bars, the types forming the row or line to be printed are always in proximate alinement after the drop of the type bars. The operator forces the lever 58 backward, that is to the right, according to Fig. 2. In doing this he causes various movements above described to take place in the mechanism. That is to say the pawl 57, by turning the ratchet wheel 56, slightly rotates the roll 54 and pulls the web 55 slightly downward to a distance representing the distance from one line to the next of the matter to be printed or impressed. The wedge bars 68—69 are forced against the inclined surface 66—67 of the guide plates 64—65 and are, therefore, forced against the respective upper and lower surfaces of the reduced portions 47 of the types, the inner or thin edges of the wedge bars lodging against the shoulders 46. At the same time this takes place the movement of the alinement bar 75 (see Fig. 9) against the rear ends of the types insures the alinement of these ends and consequently a proper positioning of the types in the particular line now under construction. The platen 62 which is faced with soft material now presses the adjacent portion of the web 55 against the faces of the types so as to cause the latter to slightly bury themselves in the web—or in other words, to leave an imprint upon the same. At the same instant when these movements are taking place the arm 79 is (see Fig. 9) swung slightly inward by the movement of the bracket 81, so that the portion 80 of the arm 79 presses lengthwise against the row 130

of type to be locked. The spacing springs 82 are adapted to yield to a certain extent, that is to an extent sufficient to equalize the spacing between the several words of the line in order that the line may be of a standard length, corresponding of course to the width of the column of matter composed. The impression being made the hand lever 58 is retracted, that is, moved to the left according to Figs. 2 and 4. The lever 44 is now raised and this causes the lifting bar 38^b to be elevated in order to restore the various type bars 33 and the guide bar 35 to their normal positions. The process above described is now repeated successively for each line of type to be composed. The impression strip thus made from the web 55 can be laid aside and at any subsequent time used as a matrix for molding either slugs or a stereotype plate as desired in order that the matter thus composed may be placed in a press and printed.

In small offices, and especially in country offices, the apparatus above described may be employed to advantage in printing and composing news items, editorials, advertisements or other appropriate matter, and the same may be saved in the form of an impression strip, which may at the end of the week, or any other appropriate period, be used for the purpose of molding the slugs or the stereotype plates as desired.

The machine described may be cheaply constructed and may be operated by a person having comparatively little training in this art. The parts are all readily accessible, and may be removed or replaced with a minimum of time and labor.

I have described the apparatus as of peculiar service in making impressions upon paper suitable for the purpose to facilitate reproduction of the matter composed at any subsequent time. It is obvious however that most of the mechanism described may be employed with equal facility for molding slugs directly against the faces of the line of type. In this event the types 49 above described will be of the kind known in this art as "matrices" or "female type," and the casting of the slugs may be performed in any manner known in this art and which I do not deem it essential to describe.

Having thus described my invention what I claim as new and desire to secure by Letter's Patent is as follows:—

55

1: A device of the character described, comprising a plurality of type bars, means controllable at the will of the operator for shifting said type bars into different relative positions in order to form a line of types selected from different bars, a hand lever, an arm connected therewith, wedge bars carried by said hand lever and said arm and provided with surfaces for fitting upon different portions of said type in order to bring said type into exact alinement, guide plates mating said wedge bars, for guiding the latter toward said type, and means carried by said hand lever and said arm for forcing against said type a transient member to be impressed thereby.

65

2. A device of the character described, comprising a plurality of types, means for bringing the same into approximate alinement, wedge bars for fitting against oppositely disposed surfaces of said types, means for guiding said wedge bars against oppositely disposed portions of said types, an alinement bar for engaging the ends of said types, means for forcing said wedge bars in one direction and said alinement bar in the opposite direction, a hand lever, means carried by said hand lever for forcing a web of paper into engagement with the face of the type, and mechanism controllable step by step by movement of said hand lever for advancing said web of paper.

75

3. A device of the character described, comprising a plurality of supporting bars each provided with a number of shoulders, a plurality of type bars adapted to be supported at different levels by said shoulders, the level at which each particular type bar is supported being determined by the degree of movement of the corresponding supporting bar, and means controllable at the will of the operator for conferring different degrees of inclination upon the respective supporting bars in order to support said type bars at predetermined levels.
